UNITED STATES PATENT OFFICE.

EUGENE F. SMITH, OF ASHTABULA, OHIO.

AUTOMOBILE-HEATER.

1,266,873.

Specification of Letters Patent. Patented May 21, 1918.

Application filed May 9, 1917. Serial No. 167,462.

To all whom it may concern:

Be it known that I, EUGENE F. SMITH, a citizen of the United States, residing at Ashtabula, in the county of Ashtabula and 5 State of Ohio, have invented certain new and useful Improvements in Automobile-Heaters; and I do declare the following to be a full, clear, and exact description of the invention, such as will enable others skilled 10 in the art to which it appertains to make and use the same.

This invention relates to automobiles and other engine driven vehicles, but more particularly to certain new and useful improvements 15 in heaters for engine driven vehicles.

The primary object of the invention is to provide a heater for engine driven vehicles adapted to receive its heat from the exhaust of the engine, and at the same time to muffle 20 said exhaust so as to overcome much of the noise necessarily incident to the running of an engine.

Another object of the invention is to improve upon devices of this class by the provision of a comparatively simple, strong, durable and inexpensive construction, and one which will be efficient and reliable in 25 operation, and well adapted to the purpose for which it is designed.

30 With these and numerous other objects in view the invention consists of certain novel features of construction and the combination and arrangement of parts which will be hereinafter fully described and claimed.

35 In the accompanying drawings forming a part of the application, and in which similar characters are used to designate like parts throughout the several views:—

Figure 1 is a diagrammatic plan view of 40 an automobile equipped with this invention;

Fig. 2 is a side elevation of the heater detached;

Fig. 3 is a vertical sectional view through the heater on the line 3—3 of Fig. 1; and,

45 Fig. 4 is a vertical sectional view taken on the plane indicated by the line 4—4 of Fig. 3.

Referring more particularly to the drawings, the letter A designates an ordinary internal combustion engine, and B the exhaust pipe of the same. Arranged beneath 50 the floor of the automobile, preferably in advance of the portion of the same above which the seats are disposed, are hollow casings or heating chambers 1, each of which is

55 formed of two asbestos-lined relatively long and narrow portions 2 and 3. The portions

2 and 3 of each casing are arranged at right angles with respect to each other, the portion 3 projecting entirely from one side to and beyond the other side of the portion 2 and 60 intersecting the latter and having its top primarily open and disposed in a plane above the upper side of the portion 2. The numeral 4 designates register plates which are fitted upon the open tops of the portions 65 3 of the casings and secured thereto in any suitable manner. Each of these register plates forms a part of the casing whose upper end it covers. As shown, the plate 4 is provided with a plurality of perforations, 70 but it is to be understood that openings of any form or configuration may be substituted for them. The lower side or bottom of the portion 3 is inclined from its outer to its inner end to assist in causing the hot air 75 from the portion 2 of the casing to be directed toward the top of the portion 3 and out through the perforated register plate.

Projecting centrally and outwardly from one end of the portion 2 of each casing is a 80 short nipple 5. The other end of the portion 2 is provided with a comparatively large opening 7 through which a tubular or cylindrical element 8 is inserted into the interior of the casing. After this is done a plate 9 85 is secured in any suitable manner to the last mentioned end of the portion 2. This plate 9 carries the centrally arranged outwardly extending nipple 10 which is similar to the nipple carried at the other end of the portion 2. The nipple 10 of one heater and the nipple 5 of the other heater are attached, by means of unions 6, to pipes C which are connected to the exhaust pipe B. The remaining unions 6 of the two casings are connected 90 together by two nipples and a short pipe section D.

As shown, the tubular element 8 is of a length such that when it is disposed longitudinally in the portion 2 of the casing, and 100 the plate 9 is secured to the proper end of the same, the pipe section will be maintained firmly in place. To prevent any possible leakage between the casing and the ends of the tubular element 8, the ends of the latter 105 are broadened or radially flanged, and a suitable packing 11 is disposed between said ends and the adjacent sides of the plate 9 and the other end of the portion 2 of the casing.

Extending transversely through the element 8 and inclining forwardly from their

upper to their lower ends is a plurality of tubes 12. As shown, these tubes 12 are arranged in two rows extending longitudinally with respect to the tubular element 8. The 5 lower end of each tube 2 is cut off right-angularly, while the upper ends thereof are cut off all in the same plane. This construction provides a means for causing circulation of the air both around the element 8 10 and therethrough by way of the tubes.

The opposite sides of the portion 2 of each casing, near their lower edges, are provided with openings 13 through which air from the outside may pass into the interior 15 of the casing.

It is to be understood that the automobile or other vehicle may be provided with as many of the heaters as it has seats, and these may be arranged in any convenient 20 manner and location in the machine, the pipe section or pipe sections D being dimensioned and shaped according to the requirements of each case.

The relatively long and narrow registers 25 are in open communication with the interior of the automobile and extend transversely of the automobile floor and through the greater part of the width of the latter, so that the heated air is dispensed in a relatively narrow and long space across the 30 floor, and several persons on the same seat of the automobile may be equally benefitted by one of the heaters. This advantage is obtained in spite of the location of the 35 portions 2 and their tubular elements at one side of the automobile. By thus locating the portions 2, however, they do not interfere with the driving shaft, nor with other centrally located parts, and are arranged in close proximity to the laterally disposed exhaust pipe B, so that the exhaust is not cooled appreciably in passing 40 from the engine to the heaters.

Because of the portions 2 being relatively 45 long and narrow and positioned as explained in the foregoing they are susceptible of the maximum capacity and air-heating surface while providing for the utmost convenience in attaching the casings to one another and to the automobile.

After the engine has been started and it is desired to heat the machine, a two-way 50 valve 14 arranged at the junction of one of the pipes C and exhaust pipe B is operated so as to cause all or a portion of the exhaust from the pipe B to pass through the heaters. This hot exhaust heats the air contained in the casing, and this heated and lightened air passes upwardly through the 55 same and out through the register plate 4

into the interior of the car. Cold air enters the casings or hot-air chambers by way of their inlet openings 13, and a considerable portion of this cold air is drawn through the tubes 12, in consequence of the air being heated therein and rising therefrom. It is obvious, therefore, that these tubes 12 65 render the heaters extremely efficient.

From the foregoing description, taken in connection with the accompanying drawing, 70 the construction, use and operation of the device will be readily understood without a more extended explanation. As various changes in form, proportion and in the minor details of construction may be re- 75 sorted to without departing from the spirit of this invention, it is to be understood that I do not wish to be limited to the precise construction herein shown and described.

I claim:

1. In a heater for engine-driven vehicles, a hollow casing formed of two relatively long and narrow intersection portions arranged at right angles with respect to each other, one of said portions of the casing including an apertured register plate through which it is in open communication with the interior of the vehicle, said portion and its registering plate extending transversely of the vehicle and through the greater portion 85 of the width of the latter, the other portion of said casing having air inlet openings therein, and a tubular element extending through said other portion of said casing and adapted to be connected to the exhaust 90 outlet of the vehicle-engine.

2. In a heater for engine-driven vehicles, a unitary structure comprising a hollow casing formed of two relatively long and narrow intersection portions arranged at right 100 angles with respect to each other, one of said portions of the casing projecting laterally of the other of said portions and extending from one side to and beyond the other side of the other of said portions, this laterally projecting portion including an apertured register plate in open communication with the interior of the vehicle, said other portion of the casing having air inlet 105 openings, and a pipe extending through said other portion of the casing and adapted to be connected with the exhaust pipe of the vehicle-engine.

In testimony whereof I have hereunto set my hand in the presence of two subscribing 115 witnesses.

EUGENE F. SMITH.
